Attorney

UNITED STATES PATENT OFFICE.

RUDOLPH TOENNES, OF BOONVILLE, MISSOURI.

COOLING DEVICE FOR MARINE ENGINES.

Application filed October 6, 1923. Serial No. 667,036.

To all whom it may concern:

Be it known that I, RUDOLPH TOENNES, a citizen of the United States, residing at Boonville, in the county of Cooper and 5 State of Missouri, have invented certain new and useful Improvements in Cooling Devices for Marine Engines, of which the following is a specification.

This invention relates to improvements in 10 cooling devices for engines, and has for its object to provide a means for such purpose which can be used in connection with marine explosive engines, especially of the outboard type, and obviating the use of a 15 force-pump for circulating the water through the water jacket of the engine.

This and other objects hereinafter set forth are attained by the means illustrated in the accompanying drawing, which shows 20 an outboard engine attached to the stern of a boat and provided with the improved cooling means.

Referring to the drawing, 10 designates 25 an out-board engine unit of a well known type which is secured to the stern of a boat by the clamp 11 and is provided with an exhaust manifold 12 and also a rudder 13 at its rear side.

Outboard engines of this character are 30 usually provided with a plunger-pump for forcing the cooling water through the engine jacket, but this method is objectionable in that, in sandy or salt waters the pump fills with grit and dirt and continuously causes trouble for the owners of the boat. This invention avoids the use of a 35 plunger-pump and consequently overcomes the serious objections mentioned.

This invention consists in locating a water-intake 14 in or attached to the rudder 13, and connecting this inlet 14 to the water jacket of the engine with a flexible pipe 15. The mouth 16 of the water-intake 14 is preferably located at the front side of the rudder 45 slightly above the axis of the propeller shaft 17, and behind the position of the propeller blades when they are at the top side of the propeller shaft during their revolution. At this point of revolution the propeller blades force the water rearwardly and 50 consequently directly into the mouth 16 of the water-intake 14 and through the same and also the pipe 15 into and through the

water jacket of the engine and discharges through a pipe 17 into the exhaust manifold 55 12 in a manner common to this class of engines.

The water-intake 14 is preferably cast in the rudder and can be either circular, square or oblong in cross-section, and is preferably 60 funnel-shaped, having a relatively large mouth and gradually tapered towards the rear side of the rudder, thereby forming a nozzle-shaped intake to increase the force 65 of the water passing to the water jacket.

As shown in the drawing, intake 14 is curved upwardly from its mouth thereby locating its discharge end 19 at the top side 70 of the rudder, and this discharge end is provided with a nipple 20, attached in any suitable manner or cast integral with the rudder, to which is secured one end of the flexible pipe 15. This flexible water connection between the engine jacket and the rudder permits the rudder to move from side to 75 side to alter the course of the boat.

Having thus fully described the invention, what is claimed is:—

1. A cooling device for outboard marine engines comprising a rudder provided with 80 a water-intake having its mouth adjacent to and to the rear of the boat propeller, and a flexible pipe connection between the discharge end of said intake and the water jacket of the engine.

2. A cooling device for outboard marine engines comprising a rudder provided with a water-intake having its mouth adjacent to and to the rear of the boat propeller, and a flexible pipe connection between the discharge end of said intake and the water 90 jacket of the engine, said water-intake being tapered from its mouth to its discharge end.

3. A cooling device for outboard marine engines comprising a rudder provided with a water-intake having its mouth adjacent to and to the rear of the boat propeller, and a flexible pipe connection between the discharge end of said intake and the water 95 jacket of the engine, the mouth of said water-intake being positioned above the axis of the propeller shaft and in alinement with the propeller blades in their topmost position.

4. A cooling device for outboard marine 100

engines comprising a rudder provided with a water-intake having its mouth adjacent to and to the rear of the boat propeller, and a flexible pipe connection between the discharge end of said intake and the water jacket of the engine, said water-intake being tapered from its mouth to its discharge end and having its mouth located at the front side of the rudder adjacent the propeller of the boat and its discharge end at the top side of the rudder.

In testimony whereof I affix my signature.

RUDOLPH TOENNES.
